United States Patent

Des. 238,231

Patented Dec. 30, 1975

238,231

LEG FOR ARTICLE OF FURNITURE

Myron M. McClain, Dayton, Ohio, assignor to Miami Valley Plastics, Lewisburg, Ohio

Filed Sept. 11, 1974, Ser. No. 505,003

Term of patent 14 years

Int. Cl. D6—06

U.S. Cl. D6—195

FIG. 1 is a perspective view of a leg for an article of furniture showing my new design.

FIG. 2 is a side view thereof.

FIG. 3 is another side view thereof.

FIG. 4 is a top view thereof.

FIG. 5 is a bottom view thereof.

I claim:

The new and ornamental design for a leg for article of furniture, as shown and described.
